(57) **CLAIM**

The ornamental design for a multi-loop finger band, as shown and described herein.

DESCRIPTION

FIG. 1 is a front view of the invention;

FIG. 2 is a top, front and end perspective view thereof;

FIG. 3 is a bottom, front and end perspective view thereof;

FIG. 4 is a front view thereof the rear being a mirror image;

FIG. 5 is a top view thereof;

FIG. 6 is a bottom view thereof;

FIG. 7 is an end view thereof the opposite end being a mirror image;

FIG. 8 is a top, front and end perspective view of a second embodiment, the only difference being the addition of a loop; and,

FIG. 9 is a top, front and end perspective view of yet a third embodiment, the only difference being the subtraction of a loop.

The broken line showing is for illustrative purposes only and forms no part of the claimed design.
